Patented Apr. 25, 1922.

UNITED STATES PATENT OFFICE.

BURT H. MACY, OF BOSTON, MASSACHUSETTS.

SELECTIVE ELEVATOR LOCK.

1,413,752.

Specification of Letters Patent. Patented Apr. 25, 1922.

Application filed April 1, 1921. Serial No. 457,725.

To all whom it may concern:

Be it known that I, BURT H. MACY, a citizen of the United States, residing at Boston, in the county of Suffolk and State of Massachusetts, have invented new and useful Improvements in Selective Elevator Locks, of which the following is a specification.

This invention relates to elevator locks which are adapted to be used in connection with elevator cars whereof the starting and stopping is controlled by a shipper cable. Locks of this type are generally mounted on the elevator car and they cooperate with knobs or buttons attached to the shipper cable to move the cable so as to stop the car when the latter has arrived at a given floor. These locks commonly have jaws which are adapted to be sprung apart so as to permit passage of the knobs on the shipper cable between them when the car is required to pass a floor without stopping, and to be brought into a position where they will interfere with an adjacent knob in order to cause movement of the cable when the car reaches the position where it is to be stopped. Such locks of prior construction, so far as I am aware, have required the personal attention of an operator in order to be put into condition for stopping the car at a selected stage, and the service of the operator for that purpose has had to be rendered when the car was approaching the selected stage and after its departure from the next stage above or below. In other words, no means or appliance has ever been known by which an unattended car of the type which is controlled by a shipper cable can be caused to stop at any selected stage or stopping place other than the next one to the stage from which it is started.

My object has been to provide in an elevator lock of the type and for the class of service hereinbefore described a selective mechanism which may be set upon starting the car from any stage and wholly automatically act to render the lock operative for stopping the car at any other selected stage, regardless of how many stages may intervene between the starting point and the selected stopping point. This object has been accomplished by simple means which I will presently describe in detail with reference to the drawings forming a part of this specifica-

tion, and my present invention consists in 55 the principles and means embodied in the device which I am about to describe and in all equivalent structures and combinations capable of accomplishing the same results.

In the drawings,—

Figure 1 is a plan view, partly broken away and shown in section on line 1—1 of Figure 2, of the embodiment of my selective elevator lock above referred to.

Figure 2 is a vertical longitudinal section 65 on line 2—2 of Figure 1.

Figure 3 is a view similar to Figure 1, but showing the jaws of the lock in their operative or locking position, whereas Figure 1 shows the jaws in their inoperative position. 70

Figure 4 is a side elevation of the lock partly broken away to show the interior of the cable guide.

Figures 5 and 6 are sectional detail views 75 illustrating the pawl and ratchet mechanism by which the selective obstructor of my improved lock is shifted step by step during the travel of the car.

Figure 7 is a detail sectional view showing 80 a latching device additional to the selective obstructor for holding the jaws in inoperative position.

Like reference characters indicate the same parts in all of the figures wherever they occur.

My selective lock is adapted to be carried 85 by an elevator car, wherefore it is mounted on a post or standard 10 which, it is to be understood, is secured to the floor or any other equivalent part of the car. It cooperates with a shipper cable 11 and with knobs or buttons or equivalent enlargements 12, 13, each tapered at one end and having a square shoulder at the other end; there being a pair of such knobs fastened to the cable 90 adjacent to each stopping place arranged with their square ends facing each other and separated far enough to admit the jaws between them, preferably in the manner usual in this art. The casing of the lock which, as 95 a whole, is designated 14, is mounted on the standard 10 and has a guiding eye or throat 15 surrounding the cable and through which the knobs thereon are adapted to pass when the car arrives at or departs from, or travels 100 past, any appointed stopping place.

Jaws 16, 17 are mounted in the casing to embrace the cable, and are adapted to be

spread apart widely enough to pass the knobs 12, 13 without interference, as shown in Figures 1 and 2, or to be brought together as shown in Figure 3, between two knobs 5 of a pair so as to interfere with the square end of the knob next encountered in the travel of the car. They are pivoted on studs or pins 18, 19 respectively, set in the case and are acted upon by springs 20, 21, respectively, which are suitably arranged to exert force tending to shift them from the position shown in Figure 1 to that of Figure 3. In its construction and mode of operation as thus far described the lock is not substantially different from those heretofore known and used, and patented, as shown in the patents to Edwin E. Angell granted May 1, 1900, and October 15, 1912.

Each of the jaws typifies any device which 20 may be carried by an elevator lock to interfere with the knobs or stops on the shipper cable in the manner just described, my claim to protection is not necessarily limited to a construction having a pair of interfering 25 members arranged as jaws, but this particular arrangement is preferred for reasons having to do with convenience and efficiency, and therefore is adopted in the form of lock here shown.

30 Each jaw is a bell crank lever and has a short arm 22 which is connected by a knuckle joint with one arm of a yoke 23 which is mounted to slide in the case. This yoke has an eye or apertured lug 24, through the aperture of which passes a trigger lever 25 which is pivoted to the case at 26 and has a finger hook or loop 27. By placing the finger in the hook or loop 27 and moving the trigger lever outward, an operator may open or spread 35 the jaws apart. A selective obstructor 28 is provided to engage the trigger lever when it is thus displaced and hold the jaws open in a positive manner. This obstructor is preferably made as a disk mounted to rotate 40 upon a pivot stud 29 and preferably having numbers or other index marks adjacent to its rim for indicating the floor or stage at which the car is to be stopped. A notch 30 in the rim of the obstructor is wide enough 45 to admit the trigger lever, when brought into the path of possible motion thereof, and deep enough to permit the trigger then to move as needed for the jaws to be closed (that is, brought into their operative position) by the springs 20 and 21. The numbers referred to run in the direction of the arrow shown in Figure 1 from the notch 30, and the obstructor may be turned by manipulation of the operator about its pivot 50 stud until any selected one of these numbers lies beside a pointer 31, or other index mark, on the trigger.

A pawl and ratchet mechanism is provided for moving the obstructor step by step dur-

ing the travel of the car. Such mechanism 55 consists of a series of ratchet teeth 32 on the under side of the disk, a pawl 33 carried by a pawl carrier 34 which is adapted to oscillate about the pivot of the obstructor, and a pusher 35 which is connected to the 60 pawl carrier by a link 36. This pusher is conveniently a bar which occupies a guide-way 37 in the case and projects into the cable-guiding eye 15, being preferably approximately radial to the pivot of the pawl 65 carrier and obstructor. It is adapted to move endwise and is pressed away from such pivot by a spring 38 contained in a socket within the end of the pusher and confined by the shoulder 39 in the casing. The 70 end of the pusher which lies in the cable guiding eye is adapted to engage the knobs or stops 12, and is provided with upwardly and downwardly projecting wings 40 of which the edges toward the cable are so 75 curved or inclined outwardly that they will ride over the knobs, even the square ends of such knobs. The normal position of the pusher is that shown in Figures 3 and 4 and by dotted lines in Figures 1 and 2. Thus 80 when the lock is carried past any knob the pusher is displaced toward the axis of the pawl carrier, and in being thus displaced it moves the pawl through the spacing of one 85 tooth of the ratchet. As there are two 90 knobs applied to the cable at each stopping place of the car, it follows that the obstructor is moved two steps whenever the car passes any floor without stopping, and one step while the jaws are being brought to 95 a level between the two knobs at one stopping place. Hence the number 1 on the obstructor (or equivalent mark indicating the nearest stopping place to the one from 100 which the car is started) is displaced from 105 the notch 30 by the distance through which the rim of the obstructor is turned by one 110 push of the pawl, and the other numbers are spaced from one another by twice this distance. The pawl here shown is a pin 115 contained in a socket 41 in the pawl carrier and resting on a spring 42, but any other form of pawl adapted to perform essentially the same function may be here used.

An important feature of the propelling 120 mechanism for the obstructor consists in the fact that a considerable variation in the extent of movement of the pusher is possible without causing any greater movement of the pawl than the distance between two adjacent 125 ratchet teeth. Referring to Figures 1 and 2 it will be seen that the outward movement of the pusher, that is, the movement away from the pivot 29, is limited by a shoulder 44 in the case which obstructs the end of the link 36; and thus establishes the limit of backing off movement of the pawl. Then the forward or feeding movement of the

pawl ceases when the link 36 becomes perpendicular to the pusher bar, and the length of this link and the position of the pivot connecting it to the pawl carrier are so determined and located that the movement of the pusher from its outer limit to the position where the link is nearly perpendicular to the path of the pusher, gives the required distance of feeding travel to the pawl. That is, a sufficient feeding travel is given when the link becomes nearly but not quite perpendicular to this path, and thereafter a considerable further movement of the pusher may take place without causing appreciable displacement of the pawl carrier; while if the movement continues until the link is swung past the perpendicular position, whatever movement is then transmitted to the pawl carrier is a retracting one of such slight extent as not to withdraw the pawl back of the next following ratchet tooth.

Thus one model or size of lock is adapted to varying conditions in which the shipper cables and the knobs or buttons are larger or smaller. In different elevator installations the shipper cables vary more or less in diameter. This causes the knobs, which are ordinarily made in two pieces and clamped together embracing the cable, to be spread more or less widely, and there may also be some variation in the width of the knobs themselves.

The pusher of my propelling mechanism is allowed to project so far in its outermost position that it will be moved by the smallest knobs on the smallest size cables far enough to shift the obstructor through one space, and the latitude given by the link motion for a further movement of the pusher without effect enables the same mechanism, having the same adjustment, to be used under conditions where larger cables and wider knobs are found.

In using my improved lock for the intended purposes, a person at the stage where the car is at rest first pulls back the trigger and then turns the obstructor disk (which can be freely turned in the direction in which the propelling mechanism drives it) until the number representing the floor at which the car is to be stopped comes opposite the pointer 31. The number thus placed is not that of the floor as numbered from the ground or the top of the building, but designates the first, second or other selected floor above or below the one from which the car is started. When this has been done, the attendant pulls the shipper rope in the proper direction for causing ascent or descent of the car as desired, and leaves it. As the lock is carried past successive knobs on the cable, the propelling mechanism shifts the obstructor disk step by

step until the first of the two knobs at the selected floor is reached, and then the notch 30 is brought into register with the trigger 25, and the jaws are immediately allowed to move into their operative position between this knob and the adjacent one. Continued movement of the car causes the jaws to interfere with the second knob at this stage and to move the shipper rope in the ordinary manner and stop the car. The action is identical whether the car rises or descends.

By the use of this invention upon freight elevators in factories and warehouses a very obvious economy in operation is effected, because it is unnecessary either to procure a special operator for the car or to require workmen to leave their work when occasion arises for moving goods from one floor to another.

I have shown in Figure 7 means by which the lock may be rendered inoperative when the car is being run by an operator. A lug or latching shoulder 45 is provided on the outer side of the trigger 25 to cooperate with a shoulder or abutment 46 on the adjacent part of the yoke 23 or its lug 24, for this purpose. When the trigger is pulled back to open the jaws, this latch shoulder rides over the inclined face of the abutment 46 and slips past the end of the abutment, which then holds the trigger displaced, and interlocked with the yoke. Then the jaws are not able to return to locking position until force is applied to the trigger to disengage it. The cooperating shoulders 45 and 46 are so shaped that their disengagement by force applied to the end of the trigger is possible but will not take place under any amount of force transmitted from the jaws through the yoke.

What I claim and desire to secure by Letters Patent is:

1. A selective elevator lock comprising a jaw, a movable obstructor adapted to hold said jaw in an inoperative position, means tending to move the jaw into operative or locking position, and means operated by the knobs on a shipper cable during the travel of an elevator car for displacing said obstructor into a position wherein the jaw is left free to become operative.

2. A selective elevator lock for use in combination with an elevator car and a shipper cable having spaced knobs at different stages; said lock comprising a jaw adapted to be placed in an inoperative position wherein it passes clear of such knobs with travel of the car, and into an operative position where it interferes with an adjacent knob, means tending to shift said jaw from the inoperative to the operative position, displaceable means arranged to hold the jaw in its inoperative position, and mechanism operable by said knobs in the

course of travel of the car for shifting said displaceable means into a position wherein it permits return of the jaw to operative position.

5. 3. A selective elevator lock comprising a member adapted to interfere with a stop on the shipper cable of the elevator, obstructing means adapted to hold said interfering member in a displaced and inoperative position, and propelling mechanism operable by the shipper cable stops for displacing the obstructing means step by step during travel of the car, said obstructing means being adapted to permit return of the interfering member into its position when displaced to a given point.

4. An elevator lock comprising a jaw, a trigger engaged with said jaw and operable to displace the same into an inoperative location, a shiftable obstructor arranged to hold said trigger in the displaced location, and a propelling mechanism operable to move the obstructing member step by step under actuation by enlargements on a shipper cable.

5. An elevator lock comprising a pivoted jaw having an arm, a trigger member suitably connected with said arm for displacing the jaw when moved in one direction, an obstructor disk having a notch adapted to admit said trigger and having a rim extending from said notch and arranged to hold the trigger in its displaced position, said disk having a series of ratchet teeth, and a propelling mechanism including an oscillating pawl arranged to cooperate with said ratchet teeth and a pusher reciprocatively arranged and suitably connected with said pawl to impart oscillative movements thereto.

6. An elevator lock comprising a casing having a guideway adapted to admit a shipper cable and knobs on said cable, a locking jaw adapted to extend into said guideway to interfere with such knobs for moving said shipper cable with movement of the car on which the lock is mounted, a pusher mounted on the lock casing projecting into said guideway and adapted to be moved by shipper cable knobs traveling relatively therethrough, an obstructor having means for holding said jaw displaced and being movable into a position wherein it permits return of the jaw to interfering position, a pawl carrier, and a connection between said pawl carrier and said pusher, whereby the movements of the former oscillate the latter, a pawl and complementary ratchet teeth, carried by the pawl carrier and obstructor respectively.

7. In combination, an elevator car and a controller shipper cable having knobs arranged in pairs adjacent to the appointed stopping places of the car, a selective lock

including jaws arranged to cooperate with said knobs in shifting the cable to stop the car, a displacer connected with the jaws for separating them, an obstructor cooperating with said displacer for retaining the latter in the position where the jaws are opened, springs acting on the jaws tending to close them, the obstructor being movable and having a recess adapted to admit the displacer when brought into a certain position, a pawl and ratchet mechanism arranged and operable to move the obstructor step by step, and a pusher movable back and forth and being connected to the pawl carrier of said pawl and ratchet mechanism, said pusher being normally projected into a position where it is encountered, and from which it is pushed away, by said shipper cable knobs.

8. In an elevator lock having an obstructor and a pawl and ratchet mechanism, including a pawl carrier, for moving said obstructor step by step, a pusher projecting into a position to be engaged and moved by knobs on a shipper cable, and a link connecting said pusher and pawl carrier and being arranged to come approximately perpendicular to the path of movement of the pusher when the pawl carrier has been moved far enough to propel the obstructor through one step of its movement.

9. An elevator lock having an obstructor, a propelling mechanism for moving said obstructor step by step, said propelling mechanism including a back and forth moving pusher, an oscillative pawl carrier, and a link connecting the pusher and pawl carrier, the parts being so arranged that the link comes approximately perpendicular to the path of movement of its connection with the pusher at the completion of the propelling movement of the pawl carrier.

10. In an elevator lock having a guide for a shipper cable, the combination thereof with a shipper cable passing through said guide, knobs on said cable, a pusher reciprocatively mounted in the lock extending into said guide, a spring tending to project the pusher and permitting the latter to be forced inward by pressure applied by knobs on the cable, an oscillative pawl carrier, a link connecting said pawl carrier with said pusher arranged to make an obtuse angle with the pusher when the latter is fully projected and to become approximately perpendicular to the pusher when the latter is displaced by one of said knobs, a movable obstructor having a series of ratchet teeth, and a pawl carried by the pawl carrier complementary to said ratchet teeth and arranged to exert propelling thrust when moved by the inward displacement of the pusher.

11. An elevator lock comprising a casing, a pivoted jaw having an operating arm, a slide in engagement with said operating arm

and having an eye, a pivoted trigger passing through said eye and being adapted when moved in one direction about its pivot to shift said slide in a manner causing displacement of the jaw, said trigger having on its outer side a latching shoulder and the eye of the slide having a complemental abut-

ment adapted to be interengaged for holding the slide and trigger in the outwardly displaced position. ¹⁰

In testimony whereof I have affixed my signature.

BURT H. MACY.
